KNOB OR THE LIKE

Averd G. Nelson, Wisconsin Rapids, Wis., assignor to Preway Inc., a corporation of Wisconsin

Filed Mar. 14, 1960, Ser. No. 59,727

Term of patent 7 years

(Cl. D50—3)

FIG. 1 is a perspective view of a knob or the like, showing my new design;

FIG. 2 is a plan view thereof;

FIG. 3 is a front elevational view thereof looking from the bottom of FIG. 2;

FIG. 4 is a side elevational view thereof looking toward the right-hand side of FIG. 3; and

FIG. 5 is a bottom plan view thereof.

The dominant features of the design are shown in full lines.

I claim:

The ornamental design for a knob or the like, as shown and described.
